HOUSING FOR A TELEPHONE ANSWERING APPARATUS

Willy Muller, 13 Guggerstrasse,
8702 Zollikon, Switzerland

Filed July 12, 1971, Ser. No. 161,373

Term of patent 14 years

Int. Cl. D14—03

U.S. Cl. D26—14 A

Fig. 1

Fig.5

Fig.6

FIG. 1 is a perspective view of a housing for a telephone answering apparatus embodying my new design;

FIG. 2 is a front elevational view thereof;

FIG. 3 is a top view thereof;

FIG. 4 is one side elevational view thereof;

FIG. 5 is the other side elevational view thereof; and

FIG. 6 is a bottom view thereof.

The broken lines are shown for illustrative purposes only.

The undisclosed rear portions of the housing are plain and unornamented.

I claim:

The ornamental design for a housing for a telephone answering apparatus, as shown and described.
